(21) Appl. No.: **29/382,945**

(57) **CLAIM**

The ornamental design for a light conductive light emitter for a light emitting diode light source, as shown and described.

(22) Filed: **Jan. 10, 2011**

DESCRIPTION

(51) **LOC (9) Cl.** **26-04**

FIG. 1 is a perspective view of a light conductive light emitter for a light emitting diode light source showing our new design.

(52) **U.S. Cl.** **D26/2**

FIG. 2 is a front view thereof, the back being a mirror image.

(58) **Field of Classification Search** D26/1-4;

313/313, 315, 316, 317, 318, 493; 315/52,
315/53, 56, 57, 58

See application file for complete search history.

(56) **References Cited**

FIG. 3 is a side view of one side thereof, the opposite side being a mirror image.

U.S. PATENT DOCUMENTS

FIG. 4 is a top view thereof; and,

D433,166 S * 10/2000 Noll D26/2

FIG. 5 is a bottom view thereof.

D435,306 S * 12/2000 McBride D26/2

The broken lines forming curvilinear shapes in FIGS. 4 and 5 represent internal boundaries of the claimed design while all other broken lines are directed to environment and are for illustrative purposes only; the broken lines form no part of the claimed design.
